UNITED STATES PATENT OFFICE.

GEORGE A. MOORE, OF MEDFORD, MASSACHUSETTS.

FLY SWATTER.

Application filed November 28, 1925. Serial No. 71,983.

This invention pertains to that type of appliances for killing flies and the like in which a light, flatly extended member is attached to an elongated handle; and it has 5 for its object the effecting of means for so combining wire netting and heavy paper as both to increase the effectiveness and durability of the swatting portion, and to permit of the application of advertising matter thereto.

In the drawings forming part of this specification, Fig. 1 is a face view of the preferred form of the swatter, viewing it on the netting side. Fig. 2 is an obverse view 15 of the same. Fig. 3 is a face view of another form of the invention.

The reference numeral 1 designates a length of wire netting preferably rectangular in outline; 2, a rectangular length of 20 heavy paper or card; and 3, an elongated wooden handle quite thin and flexible. In both forms of the invention, the corners 8 of the netting and of the card are folded over to meet along the center line of the 25 handle and enclosing the terminal portion thereof. Then staples 4 are driven through the four layers of netting and card and the handle between.

In the form of the invention shown in 30 Fig. 3, the lateral edges 5 of the card are folded over the edges of the netting and fastened by staples 6, 7; as also the terminal edge 9 which is held by the staples 7, 6. While this makes a good fly swatter, it is 35 liable to produce an air current as it descends upon a fly, which may either warn the insect and give it opportunity for escape, or actually blow it away.

I prefer, therefore, to form a series of 40 longitudinally disposed slots 10 through the card 2, as shown in Fig. 2, by means of

which the air can readily pass. In this construction, I do not fold over the lateral edges of the card, but merely the terminal edge 9. The lateral edges of the netting are 45 however preferably folded over, as at 11, and staples 12 put through the same and the card beneath.

In using this swatter, the netting face 1 is carried downward, and, as it descends 50 upon the fly, the air pressure causes the card to belly upward slightly so that the wire meshes will alone strike and kill the insect and will not scatter its remains about the surface upon which it had alighted. 55

The value of the card 2 lies in the slightly increased weight given to the swatter and consequently greater efficiency; in the increased durability of the device, and in the opportunity provided by which suitable advertising matter can be printed thereon. 60

What I claim as my invention is:

1. A fly swatter comprising a thin elongated handle, a length of wire netting and a length of heavy paper superposed thereon 65 and marginally attached together, the corners of the netting and paper at one end being folded over onto the terminal portion of the handle and stapled thereto.

2. A fly swatter comprising a thin elongated handle, a length of wire netting, a length of heavy paper having one end folded over the end of the netting and stapled together, the opposite ends of the netting and paper having their corners folded over 75 onto the handle and stapled together; the lateral edges of the netting being doubled and stapled to the paper.

In testimony that I claim the foregoing invention, I have hereunto set my hand this 80 20th day of November, 1925.

GEORGE A. MOORE.
